UNITED STATES PATENT OFFICE

2,455,836

BOX BLANK SEPARATOR

Marinus Van Brummelen, New York, N. Y.

Application July 11, 1947, Serial No. 760,477

6 Claims. (Cl. 271—1)

1

This invention relates generally to box making machines, and more particularly to a box blank separator which is a device for consecutively separating individual box blanks from a plurality of such blanks stacked on a rack.

A primary object of this invention is to overcome the tendency of the boxes to catch on each other and to jam, as these boxes are moved from a rack onto a conveyor in conventional machines used in the box making industry, particularly to overcome the tendency of boxes having slits or windows to jam when an end of a box blank contacts the edge of the slits or window openings in another blank.

Another salient object of this invention is to provide a rotary separator having an anti-frictional member adapted to project through the window opening of such a blank, shifting the outermost blank from a plurality thereof stacked a rack, and bearing against the underlying blank to prevent the same from shifting from the rack.

Still another object of this invention is to provide a rotary separator with a plurality of arms, and means to render one or more of these arms inoperative. When two of these arms are provided, rendering of one of the arms inoperative will halve the rate at which the blanks are fed, when the device is turned at the same rotational speed.

Still another object of this invention is to provide means for a device of this character to prevent the blank contacting members from moving rapidly relative to the rotating disk whereon they are supported, this feature preventing vibration and erratic action of the separator.

And a last object to be specifically mentioned is to provide a device of this character which is relatively inexpensive and practicable to manufacture, extremely simple to adjust and use, and which will give generally efficient and durable service.

With these objects definitely in view, this invention resides in certain novel features of construction, combination and arrangement of parts and portions as will be hereinafter described in detail in this specification, particularly pointed out in the appended claims, and illustrated in the accompanying drawings which form a material part of this application, and in which:

Fig. 1 is a top plan view of the separator mounted on a drive shaft, together with a rack and a plurality of box blanks having windows therein and stacked on this rack;

Figure 2 is a side elevational view of the structure shown in Figure 1 and also including a frag-

2

mentary portion of a conveyor positioned to receive the blanks as they are fed from the rack;

Figure 3 is another side elevational view of the assembled separator, the view being taken 5 from the side opposite to the side illustrated in Figure 2;

Figure 4 is a vertical transverse sectional view of the separator, taken on the line 4—4 in Figure 3 and in the direction of the arrows; and,

10 Figure 5 is a side elevational view of the disk used to mount the arm portions of the separator, portions of the disk being broken away and the underlying portions shown in section and elevation to illustrate how the two halves of the disk are connected.

Similar characters of reference designate similar or identical parts and portions throughout the specification and throughout the several views of the drawings.

15 Referring now to the drawings in detail and having, first, particular reference to Figures 1 and 2, it will be noted that the environment where-with this invention is adapted to be used includes a drive shaft 10, a rack 12 illustrated diagrammatically in the views to represent any conventional type feeder rack whereon box blanks 14 are stacked. This invention is particularly adapted for use in feeding box blanks which are apertured or windowed as at 16 and these blanks will ordi-

20 narily be fed outwardly from the leading edge 18 of the rack onto a conveyor 20. It will be understood that the blanks 14 may be in any one of many stages of manufacture, the windows 16 having already been formed therein, and that the 25 same blanks will be transmitted by a conveyor 20 or some analogous structure to be operated upon, as in the application of adhesive or the application of Cellophane coverings for the window 16.

The disk, generally indicated by the numeral 30 30 in Figure 5, is constructed in two parts 24 and 26, the part 26 having secured therein aligning pins 28 and the part 24 having bores adapted to register with and to receive the ends of these aligning pins. Elongated studs 30 are inserted 35 through suitable bores formed in the part 26 and are threadingly engaged in aligning bores which are threaded in the part 24, thus facilitating the attachment of the disk to the drive shaft 10. It will be understood that conventional means such 40 as splines or keys may be added to assure rigid connection of the disk 22 on this shaft. Each of the parts of the disk are provided with transversely disposed arcuate slots 32 for the purpose hereinafter made abundantly clear. The rocker 45 arm 34, preferably of slightly S-shape is provided

50 as splines or keys may be added to assure rigid connection of the disk 22 on this shaft. Each of the parts of the disk are provided with transversely disposed arcuate slots 32 for the purpose hereinafter made abundantly clear. The rocker 55 arm 34, preferably of slightly S-shape is provided

in duplicate and pivoted to the disk by bolts 36 which may have incorporated therewith any suitable bearing structure, these bolts 36 being threadingly engaged in bores tapped and threaded in the disk 22. It should be noted that one of the rocker arms, that designated as 34' is formed with an aperture 38 and an adjacent portion of the disk is apertured as at 40, so that the arm may be moved into what is hereinafter referred to as the retracted position and retained in this position by inserting a bolt through the apertures 38 and 40, one of these apertures being preferably threaded to facilitate the securement of this attaching bolt in place. If preferred, this attaching bolt may be carried on the disk by tightly threading the same therein, as indicated at 42 in Figure 3.

One end of each arm 34 and 34' is provided with a transversely disposed journal member 44 and a bearing member 46 whereby a roller 48 is freely rotatably mounted. The other end of each arm is provided with a pin 50 rigidly secured therein and extending in both directions from the arm, the portion thereof extending toward the disk 22 being accommodated by the slot 32 and carrying the sleeve bearing 52. A spring 54 is terminally secured to the pin 50 and to a bolt 56, so as to bias the rocker arm in one direction. The other end of the pin 50 is pivotally secured, as at 58, to the outer end of the piston rod 60. This piston rod 60 is connected to a piston 62 comprising a metal washer and a flexible washer and adapted to reciprocate within the cylinder 64. The disk 64 is provided with a projecting lug 66 which is apertured to receive a pivotal attaching screw 68 threadedly engaged in the disk 22 and provided with a lock nut 70 and a spacer sleeve 72. The structure detailed above comprises a substantially conventional dash pot which may be generally indicated by the numeral 74, and it will be understood further that a suitable cap 76 will be threadedly engaged on the outer end of the cylinder 64 and that the base of the cylinder 64 will be provided with a very small aperture 78 in conventional manner. It will be understood that the spring structure and the dash pot structure is in duplicate and similarly associated with the arms 34 and 34'.

The operation of this invention will be clearly understood from the foregoing description of the mechanical details thereof, taken in connection with the above recitation of the objects sought to be achieved by this invention. In recapitulation, the rollers 48 are consecutively brought into contact with the blanks 14, a portion of the roller passing through the window 16 in the blank and bearing upon the blank underlying that blank which is shifted by the roller 48. The Figure 2 clearly shows the main principle of operation of this invention, since this figure illustrates how the roller will prevent the underlying blank from moving away from the rack 12. Each of the rollers 48 is dimensionally adapted, as to width and diameter, for partial entrance into, and frictional engagement with the edge of a window 16 in the outermost of a stack of blanks 14, during the operation of the device. The roller will have rolling friction only with the immediately succeeding and underlying blank, while more forcefully engaging and shifting the outermost blank. Although the dimensioning of the roller and other portions of this invention is critical, it is believed that those skilled in the art to which this invention appertains will be enabled to construct and to use a machine according to this

invention and this disclosure of the invention, without the inclusion in this disclosure of the specific dimensions of the various parts. The device is so constructed that exacting adjustment of the biasing means for the arms is not required, and substitution of different springs 34 may be used to adjust the device when required, it being obvious that many suitable means may be incorporated with these springs to make the same adjustable and that such minor modifications of this invention fall within the spirit and scope thereof. It is also within the scope of this invention to substitute means differing from the roller structure illustrated in the drawings and though there has been shown a particular embodiment of this invention, this application is not limited to this particular embodiment, but it is desired to include in the scope of this invention the construction, combination and arrangement of parts and portions substantially as set forth in the appended claims.

Having described the invention, what is claimed as new is:

1. A device for consecutively separating individual blanks having windows from a plurality of such blanks stacked on a rack, comprising a disk rotatively mounted adjacent the leading edge of a rack, a rocker arm pivoted on the side of said disk, and means to bias said arm into a position with one end thereof extending radially beyond the periphery of said disk, said one end having a journal, and a roller freely rotatably mounted on said journal, said roller being dimensionally adapted for partial entrance into, and frictional engagement with the edge of, a window in the outermost of a stack of blanks, the roller having rolling friction only with the succeeding underlying blank after said outermost blank has been shifted by the roller.

2. A device for consecutively separating individual blanks having windows from a plurality of such blanks stacked on a rack, comprising a disk rotatively mounted adjacent the leading edge of a rack, a rocker arm pivoted on the side of said disk, means to bias said arm into a position with one end thereof extending radially beyond the periphery of said disk, a roller freely rotatably mounted on said one end, and a shock absorber operatively connected to and between said arm and disk to retard the movement of said arm relative to said disk, said roller being dimensionally adapted for partial entrance into, and frictional engagement with the edge of a window in the outermost of a stack of blanks, the roller having rolling friction only with the succeeding underlying blank after said outermost blank has been shifted by the roller.

3. A device for consecutively separating individual blanks from a plurality of such blanks stacked on a rack, comprising a disk rotatively mounted adjacent the leading edge of a rack, a rocker arm pivoted on the side of said disk, means to bias said arm into a position with one end thereof extending radially beyond the periphery of said disk so that said end will consecutively contact and shift said blanks when the disk is rotated, and a double acting dash pot connected between the outer end of said arm and said disk to retard motion of the arm relative to said disk and thus to prevent undue vibration in the device.

4. A device for consecutively separating individual blanks from a plurality of such blanks stacked on a rack, comprising a disk rotatively mounted adjacent the leading edge of a rack, a

rocker arm pivoted on the side of said disk, and means to bias said arm into a position with one end thereof extending radially beyond the periphery of said disk so that said end will consecutively contact and shift said blanks when the disk is rotated, said disk being divided to facilitate the mounting thereof on a drive shaft, a second similar arm on said disk, and means for retaining one of these arms in retracted and inoperative position.

5. A device for consecutively separating individual blanks having apertures from a plurality of such blanks stacked on a rack, comprising a disk rotatively mounted adjacent the leading edge of a rack, a rocker arm pivoted on the side of said disk, and means to bias said arm into a position with one end thereof extending radially beyond the periphery of said disk, said one end having anti-friction means to project successively through an aperture in each of said blanks and to bear against an underlying blank with less friction than that applied against the outermost blank preventing the shifting of said underlying blank while shifting the outermost blank.

6. A device for consecutively separating individual blanks having apertures from a plurality of such blanks stacked on a rack, comprising

a disk rotatively mounted adjacent the leading edge of a rack, a rocker arm pivoted on the side of said disk, and means to bias said arm into a position with one end thereof extending radially beyond the periphery of said disk, said one end having a roller to project successively through an aperture in each of said blanks and to bear against an underlying blank with less friction than that applied against the outermost blank preventing the shifting of said underlying blank, while shifting the outermost blank.
